RING WELT AND METHOD OF MAKING

Pearl C. Arnold, West Hanover, Mass., assignor to
 Barbour Welting Company, Brockton, Mass., a
 copartnership composed of Perley E. Barbour,
 Walter G. Barbour, and Richard H. Barbour

Application April 24, 1935, Serial No. 17,987

6 Claims. (Cl. 36—78)

This invention relates to shoe welting and more particularly to shoe welting prepared in a special form for use in the manufacture of completely welted shoes. The welting is especially desirable for shoes having an upper too short to overlant such, for example, as disclosed in my co-pending application for Welting and shoemaking therewith, Ser. No. 664,742, and in the co-pending application of William C. Vizard for Welting and shoemaking therewith, Ser. No. 664,722, both filed April 6, 1933.

The purpose and method of manufacture of the welting claimed herein will be best understood from the following description with reference to the accompanying drawing, in which:

Figure 1 is a view, in perspective, of a fragment of a strand of welting material, preferably grain leather, of the kind disclosed in my application Ser. No. 664,742, having three separable flaps at one edge;

Fig. 2 is a view, in perspective, of a measured length cut from said strand having each end face-scarfed in accordance with the usual practice in the manufacture of unlimited long welted fillets;

Fig. 3 is a view, in perspective, of the piece shown in Fig. 2 manipulated to form an endless welt for a single shoe upper;

Fig. 4 is a view, in perspective, of a portion of the ring welt of Fig. 3 showing the outer flap broken down from the other two to facilitate cementing its inner face and that of the adjoining flap; and

Fig. 5 is a view, in cross section, of the ring welt attached to a short shoe upper and having its extension broken back preparatory to assembling with an insole for lasting.

In the following description the manufacture and use of the welting of this invention will, for simplicity, be confined to the processing of grain leather, but it should be distinctly understood that the usefulness of this invention is not limited to leather because any suitable welting material may be processed and used in like manner; nor are dimensions given because they vary greatly with the size and kind of shoe for which the welting is made. The general field of usefulness of the welting includes children's, growing girls', misses', little gents' and boys' shoes; work shoes for all ages; and sport shoes, particularly of the serviceable type.

In the embodiment of the invention illustrated in the drawing a strand 10 of grain leather is slit twice transversely through one edge producing a grain-faced flap 12, an adjoining or central flesh

flap 13 preferably of somewhat lighter weight and a second flesh flap 14 preferably of substantially the weight of the grain-faced flap. The slits are limited in depth leaving an unslit or solid body 15 that, in the shoe, is outturned from the upper and provides the welt extension. The slits may be made in an unlimited long strand of welting, and if so, the next step is to cut a piece from the strand that, when formed into an endless welt or ring, will neatly fit to the periphery 10 of the short upper at its lower edge.

Accordingly a measured length 20 may be cut from a previously slotted strand substantially equal to the distance around the bottom of the upper for the size of shoe being processed, allowing for a lap of the two ends in order to make a strong joint in the ring. It will be understood that, if desired, unslit measured lengths may be obtained in any feasible way and these pieces edge-slit separately to form three flaps. The measured length, however obtained, is oppositely face-scarfed at each end, as at 22 and 24 (Fig. 2) the length of the scarf being such that when lapped to form a ring the measurement for fitting exactly to the upper is retained. The two scars are cemented, lapped and pressed producing a tubular ring welt 25 (Fig. 3), that is, tubular in the sense that the axial dimension of the strand forming the ring is greater than the radial dimension thereof, thus distinguishing from ring welts known to the prior art and shown, for example, in Fig. 5 of U. S. patent to Fleming, No. 1,150,181, August 17, 1915. It will be observed that the flaps 12, 13 and 14 are at one end of the short tube formed by the width of the welting strand. The ring is so formed as to leave the grain of a leather strand on the outer or circumferential face of the short tube.

The grain flap 12 and adjoining flesh flap 13 may now be opened and cement applied to their inner faces. Thereafter the lower edge of the short shoe upper may be tucked in between these two cemented flaps and light pressure applied to hold the upper and welt together while being stitched. It is important that the welt is placed evenly on the upper and to further this end the outer or grain flap 12 may be broken down as shown in Fig. 4 and the shoulder 26 may be used as a gauge in laying the upper on the cemented face of the flap 13. This feature is not a part of this invention but will be found disclosed and claimed in the co-pending application of William C. Vizard, Ser. No. 17,993, filed of even date therewith.

The combined upper and ring welt are now

ready to receive the stitching 30 (Fig. 5) by running through a sewing machine in the manner described in my said application Ser. No. 664,742 or in any other convenient manner.

5 The upper having been permanently secured between the two flaps 12 and 13 of the welt, the welt is now prepared for lasting by tempering and then breaking the extension 15 outward relatively to the secured upper and by causing the third 10 flap 14, or lasting allowance, to stand somewhat inward of the upper (see Fig. 5). Thereafter, upon assembling with an insole upon a last, lasting may be proceeded with substantially as described in the said application, Ser. No. 664,742 15 or otherwise as suited to the type of shoe being built.

Those skilled in the art will recognize that my invention relates, in its broader aspects, to all 20 weltings having a plurality of separable flaps at one margin for embracing the lower edge of a scant shoe upper such, for example, as disclosed in said prior filed applications hereinbefore referred to. Some of the claims herewith, accordingly, set forth this characterizing feature of the invention 25 by the intentional use of generic terms and expressions inclusive of various modified forms of the welt.

The nature and scope of the invention having 30 been indicated and the preferred form of a tubular ring welt for application to a scant shoe upper together with the process of producing it having been specifically described, what is claimed as new, is:—

35 1. A pre-formed tubular ring welt for the complete weltling of a single shoe comprising a piece of weltling edge-slit to form three separable flaps at one margin and having an unslit extension integral therewith, the ends of said piece being

lapped across said flaps and extension and secured together.

2. A tubular ring welt pre-formed from a measured length of a grain leather weltling strand having a grain flap and two flesh flaps at one margin 5 and a solid extension integral therewith, the ends of said length being lapped across said flaps and extension and secured together with the grain presented at the circumferential face of the ring.

3. A pre-formed tubular ring welt comprising a 10 measured length from a strand of weltling characterized by a transversely slitted edge providing flaps at said edge, said edge-slitted length having its ends oppositely face-scarfed through its flaps, and said scarfs being lapped and secured to each 15 other.

4. A pre-formed tubular ring welt characterized by a plurality of separable flaps at one end of the short tube formed by the width of the weltling strand. 20

5. The method of making a welt for the subsequent complete weltling of a single shoe which comprises forming a plurality of separable flaps by transversely slitting the edge of a piece of weltling, oppositely face-scarfing the ends thereof, 25 thenlapping and connecting said scarfs forming a tubular ring, whereby said flaps are presented at one end of the short tube formed by the width of the piece of weltling.

6. The method of making a ring welt off the 30 shoe which comprises forming a plurality of separable flaps at one margin of an unlimited long strand of weltling by transversely slitting one edge thereof, severing a measured length from said slitted strand, oppositely face-scarfing the ends 35 of said measured length, through its flaps and forming a tubular ring by cementing, lapping and pressing said scarfs.
